UNITED STATES PATENT OFFICE.

THOMAS W. BARRY, OF CHICAGO, ILLINOIS.

WINDOW-REFRIGERATOR.

980,397.

Specification of Letters Patent.

Patented Jan. 3, 1911.

Application filed May 21, 1909. Serial No. 497,486.

To all whom it may concern:

Be it known that I, THOMAS W. BARRY, citizen of the United States, residing at Chicago, in the county of Cook and State of Illinois, have invented new and useful Improvements in Window- Refrigerators, of which the following is a full, clear, and exact description.

The object of my invention is to provide a simple and economically constructed window refrigerator, that can be easily adjusted and secured in the frame of the window of a pantry or other room in such manner as to keep out flies and other insects; which can be opened only by raising the lower sash, and yet does not interfere with the movements of the same, and which is practically dust proof and rain proof while permitting the free circulation of air therethrough. This I accomplish by the means hereinafter fully described, and as particularly pointed out in the claims.

In the drawings:—Figure 1 is a perspective view of my invention showing the door open. Fig. 2 is a vertical longitudinal section thereof taken on line 2—2, Fig. 3. Fig. 3 is a transverse vertical section.

My invention consists of a rectangular or box-shaped metallic casing A, the top and bottom, the vertical end walls and the outer vertical walls of which are closed, except for ventilating openings therein, substantially as hereinafter fully explained. The edges *a* of the front or inner vertical side of this casing, A, are beaded by rolling said edges outward around a heavy wire, and the end-walls are connected by cross-strips or rails *b*, *c*; about an inch, say, back from the vertical plane of said beaded edges *a*. The lower rail *b*, is, preferably, made by taking a strip of sheet metal of sufficient width; seaming one edge of it around the heavy wire used as a filler for the lower edge *a* of the casing; then bending it back upon the bottom of the casing a short distance, and then bending it vertically a short distance and seaming its upper edge. The upper rail, *c*, consists of a transverse strip or bar of metal that connects the sides of the casing at points back from the forward beaded edges thereof, in the same vertical plane as the vertical portion of the lower rail. The interior of this casing is divided into an upper and lower compartment by a floor B, consisting, preferably, of a sheet metal plate, whose flanged edges are soldered or otherwise suitably fastened to

the vertical walls of the casing, and to the inner surface of the upper rail, near the lower edge thereof. The lower compartment is closed in front by a door C, the lower edge of which is hinged to the upper edge of the lower rail, *b*, and which is held closed by a spring bolt *d*, secured to the outer surface of the center of length of the upper edge of said door, and engaging a suitable companion socket *e* suitably secured to the upper rail. The upper compartment is likewise closed by a door D, the lower edge of which is hinged to the upper edge of the upper rail, and this upper door also has a spring-bolt *E*, secured to the center of length of its upper portion, which is adapted to engage an opening or recess *f* in the overhanging upper front edge of the casing. As seen in the drawings, these upper and lower doors preferably have flared edges *X* of sufficient width to fit snugly against the portions of the side and top walls of the casing that extend beyond the vertical plane of the front wall heretofore described. This is done by bending the edges of the doors laterally at right angles to themselves and then outwardly again in a plane parallel to the main portion of the door, so as to form a substantially L-shaped seat. The portion of the outer flange nearest the pivotal hinge for the door is cut away at each end of the door, so as to form shoulders *x*, which latter, when the door is opened, are adapted to abut against the projecting edges of the side-walls, as will be readily understood.

In order to provide for the ventilation of my improved refrigerator, I make a horizontal series of openings *g* in the upper portion of the rear wall of the upper chamber, and also a series of openings *h*, *h*, in the upper portion of each side-wall thereof, and I make a series of ventilation openings *j*, *j*, in each side wall of the lower chamber, substantially as shown in the drawings. These ventilation openings are respectively closed by screens G and H and J, that, preferably, consist of a strip of fine and a strip of coarse wire mesh; one of said strips being of such greater dimensions that its edges can be lapped over and made to clasp the edges of the other. Suitable horizontal strips *k*, *k* are secured to the walls of the casing, both above and below said ventilation openings, whose longitudinal edges nearest said openings are separated from the walls sufficient to enable them to serve as guide-ways for

said screens and in which said screens can be slid in or out. The strips *k* for the rear openings *g* being, preferably, on the outside, and the others on the inside of the walls.

5 I prefer to make the roof of the refrigerator incline outward and have eaves that overhang the outer-wall of the casing, and near the front or inner beaded edge, I secure a transverse bar, *K*, of metal, the ends *m* of which extend beyond the sides of the casing slightly and are upturned as shown, and provided with screw openings. When the refrigerator is set in the window properly it will rest upon the sill of the window-frame, 10 and be secured thereto by screws inserted through openings *I*, *I*, in the lower inner projecting edge, and the ends of the bar *K* will be inserted in the lower portion of the runway for the upper sash of the window, 15 and the bar lowered until it rests upon the roof of the casing, as shown, and then be secured thereto by one or more screws *n*, and then the ends of the bar *K* secured to the window-frame by screws inserted through 20 the screw-holes therein.

What I claim as new is:—

1. A window refrigerator comprising a rectangular box divided horizontally into compartments and the front wall of which is 30 partly cut away, doors closing said cut away portions, vent openings in each of said compartments, perforated plates closing said vent openings and a longitudinally disposed bar secured to the top of said box, having 35 its ends extended beyond the end walls thereof and adapted to be secured to the frame of a window.

2. A window refrigerator comprising a rectangular casing divided into compartments, the front wall of said casing being partly cut-away and the forward edges of the side-walls projecting beyond the plane of said front-wall, and a door closing said cut-away portion and provided with flared edges that engage the projecting edges of the side-walls, a portion of the flared edge on each side of said door nearest its hinge being displaced to form shoulders that abut against the adjacent projecting edges of the side-walls when said door is opened. 40

3. A window refrigerator comprising a rectangular casing divided into compartments, the front wall of said casing being partly cut-away and the forward edges of the side-walls projecting beyond the plane of said front wall, a door closing said cut-away portions and provided with flared edges that engage the projecting edges of the side-walls, a portion of the flared edge on each side of said door nearest its hinge being displaced to form shoulders that abut against the adjacent projecting edges of the side-walls when said door is opened, and a longitudinally disposed bar secured to the top of the casing and having a lateral projection at each end adapted to be secured to the frame of the window. 45

In witness whereof I have hereunto set my hand this 17th day of May 1909.

THOMAS W. BARRY.
